(57) **CLAIM**

The ornamental design for a protective case for a test and measurement instrument, as shown and described.

DESCRIPTION

FIG. 1 is a top, front, right, isometric view of a protective case for a test and measurement showing the new design in an environment of use;

FIG. 2 is a bottom, rear, left isometric view thereof;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear elevational view thereof;

FIG. 9 is a right side elevational view thereof shown in an alternate position;

FIG. 10 is a front elevational view thereof shown in an alternate position;

FIG. 11 is a top, front, right, isometric view of the protective case for a test and measurement instrument of FIG. 1 shown without environmental subject matter;

FIG. 12 is a bottom, rear, left isometric view thereof;

FIG. 13 is a front elevational view thereof;

FIG. 14 is a right side elevational view thereof;

FIG. 15 is a left side elevational view thereof;

FIG. 16 is a top plan view thereof;

FIG. 17 is a bottom plan view thereof; and,

FIG. 18 is a rear elevational view thereof.

Broken lines illustrate portions of the protective case for a test and measurement instrument that form no part of the claimed design. Additional broken lines in FIGS. 1-10
